YARN WINDING MACHINE

Louis M. Cotchett, Hingham, and Lester Campbell, Ferdinand F. Stange, and Alfred W. Arterton, Westfield, Mass., assignors to Foster Machine Company, Westfield, Mass., a corporation of Massachusetts

Application February 3, 1944, Serial No. 520,886

24 Claims. (Cl. 242—35.6)

The present invention relates to new and useful improvements in winding machines and more particularly to novel and improved means in such machines for realizing continuance of winding of a supply of yarn and a package.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a plan view of a winding machine typical of the kind to which this invention can be successfully applied;

Figure 2 is a vertical section of one of the winding units of Figure 1 and associated parts, embodying a typical and illustrative form of the present invention;

Figure 3 is another vertical view similar to Figure 2 but showing different details;

Figure 4 is an elevation of a detail of the apparatus forming this invention, as embodied;

Figure 5 is a detailed view of the duct member illustrated in Figures 3 and 4;

Figure 6 is a detailed view of cam actuating mechanism forming part of the embodied apparatus;

Figure 7 is another detailed view of the cam actuating mechanism of Figure 6 with certain additional operating elements;

Figure 8 is a detailed view of the mechanism of Figure 6 with the operating parts in different relative positions;

Figure 9 is a view similar to Figure 7 but showing the parts in the different relative positions of Figure 8; and

Figure 10 is a fragmentary view with certain parts broken away of a portion of the apparatus particularly showing the suction and blowing nozzle in accordance with the invention.

The present invention has for its object, broadly, to provide in a winding machine means for readily and quickly finding the yarn end on a package which is partially wound and withdrawing this yarn end to a position where it can be

readily united with the yarn end of a supply bobbin.

A further object of the invention is to provide, in a winding machine, means whereby a predetermined and controlled length of yarn may be withdrawn from a partially wound package and placed in a position to be readily united with the yarn from a supply of yarn. A further object of the invention is to provide automatic means for drawing a measured length from a package of a winding machine and locate this for ready tying with the free end of yarn of a supply mass. Other objects of the invention are: to provide means to facilitate finding the end of the yarn thereon; to provide means to permit the drawing of a yarn end from such a package along a predetermined path; to automatically have such a free end picked up and associated with an end of yarn from a supply source, for easy and rapid tying; and to have all these steps performed automatically in correct sequence for operations of assembling an end of the yarn on the package with an end of a supply mass.

In the preferred embodiment of the invention herein disclosed, the invention is illustratively applied to a multi-unit winding machine having a plurality of surface driven winding units arranged in a continuous series, each winding unit comprising a constantly rotating driving roll, a pivoted arm carrying a package core receiving spindle or shaft which can be lowered to bring the core into driving relation to the roll so that yarn or other filamentous material is wound on the package by the rotation of the roll and core. Usual yarn guide means are traversed back and forth across the surface of the package to wind the yarn properly on the core.

The winding units are preferably identical and may be divided into two groups of about fifty each, the two groups facing in opposite directions, while the driving rolls for each group are aligned, mounted on and driven by a common shaft, each of the two group shafts being driven by a separate motor at the desired winding speed.

Cooperating with the several winding units in succession, and moving relatively to them is a tender, and means are preferably provided for moving the tender past the several winding units which are preferably fixed with reference to the machine frame. The tender is supported by and moves on a trackway, which trackway preferably extends along the multi-unit winding machine near its base and forms an endless track having two straight portions parallel to each other, one at either side of the machine, these straight por-

tions being connected at the ends by curved track portions which provide an endless path, of generally oblong shape. The tender is driven on said track by suitable means which may include an electric motor which is driving connected with traction devices carried by the tender and engaging the trackway.

In accordance with this invention, the tender also includes a suction nozzle which is preferably relatively thin, of a width greater than the package being wound and is directed toward the package, so that after the yarn has been exhausted from a supply bobbin or the supply yarn is broken, the loose yarn end on the package may be automatically found and sucked into the nozzle by the current of air. To provide for the suction, the tender carries a blower which may be conveniently electrically driven by a motor, and the suction nozzle is connected to the intake side of the blower by an air duct extending for a considerable distance in a generally downward and outwardly direction away from the package.

As the tender moves forward, it comes to a winding unit and the suction nozzle is moved forward and close to the periphery of the package, thereby sucking the yarn end into the suction nozzle. The duration of association of the nozzle near the package is regulated with the unwinding braking mechanism to draw off the desired length of yarn. Continued movement of the tender causes a hook to move through a slot in the suction duct and to engage the yarn end and withdraw it to a position to be assembled, properly spaced and parallel, with the yarn end from the new supply. After that, the two ends may be united by a knotting device, or manually. Suitable cams are provided, to obtain these operations in correct sequence and timing. Reversing means are preferably applied to the package prior to or simultaneously with the application of suction.

Furthermore, as embodied, means are provided to expedite and insure the freeing of the yarn end from the surface of the package, comprising a blowing nozzle immediately next to the suction nozzle, the exhaust air from the blower being directed to flow along the top of the suction nozzle so that, when the suction nozzle is extended, an opening is formed by the mouth of the nozzle and its supporting casing so that the exhaust blast is caused to impinge tangentially across the periphery of the wound package before being drawn into the suction nozzle mouth, thereby considerably enhancing the sweeping action of the air current to blow free, lift and draw off the loose end from the wound package into the suction nozzle.

Means are also preferably provided for causing the package to rotate in a reverse direction during the application of suction thereto, to facilitate drawing off the desired length of yarn.

To this end, there is provided an idle, intermediate roll, mounted in a bracket that is swingably fastened to the movable duct, is intermittently brought into engagement with the constantly rotating driving roll and the stationary package when said duct is extended which causes the intermediate roll to start rotating by frictional contact with the driving roll, and the package to start rotating by frictional contact with the intermediate roll, said intermediate roll being positioned in frictional contact between the driving roll and the package causes the package to rotate in a reverse or unwinding direction.

Also as embodied, along the trailing edge and at the underside of the suction duct is provided a long narrow slot extending into the nozzle, and for a considerable distance toward the blower, and means are provided for engaging the yarn drawn into the suction duct and for removing it from the duct through this long narrow slot.

For this purpose a second slot, parallel to the path of movement of the tender, intersects the long narrow slot, and a hook member is provided on each winding unit on the frame which hook may enter and pass through the second slot as the tender moves. During this passage the hook engages the yarn lying in the duct so as to slide the yarn laterally of the duct and finally through the long narrow slot, the length of yarn having been predetermined, and being more than sufficient to extend past the second slot. Preferably this yarn engaging and removing hook is associated with a clamp which holds and carries the leading end of the yarn from the reserve supply bobbin so as to assemble the leading end of the reserve yarn supply with the exhausted end of the yarn wound on the package, thereby positioning the two yarn ends readily for tying, either manually or by a mechanical knitter.

The knitter may be of conventional design, and if mechanical is preferably mounted on the tender so as to receive, engage, trim, and tie the assembled yarn ends into a secure knot of the desired type. Where the mechanical knitter is carried by the tender, it is preferably actuated in correct timed relation, by the travel of the knitter past the winding unit.

Thus each winding unit continues to wind yarn from a supply mass or bobbin onto a package by contact of the package with the driving roll, and when the yarn supply has been exhausted, the bobbin is doffed from its supporting pin which is now ready to receive a new supply mass dropped onto it by the operative. As the operative drops the new bobbin into place, its leading yarn end is held and preferably placed in a clamp adjacent the hook to ready it for the subsequent passage of the tender and knitter.

Means are provided cooperating with the tender and controlled by a starting lever, by which the idle package is brought into driven position with respect to its driving roll. As embodied the starting lever has a running position and an off position, and cam means are provided on the tender to be engaged by the starting lever only in its off position, this engagement being necessary to cause actuation of the various tender-carried parts cooperating with the winding unit.

If the yarn has been exhausted, the means have caused movement of the package to be raised to its stopped or idle position, and the tender carrying mechanisms are engaged by the starting lever in its consequent off position, and thereby causes actuation of the various tender-carried parts.

Cam means are provided for resetting the starting lever as the final operation of the tender on the winding unit, these means operating, of course, only in case the starting lever is not already in running position.

It will be understood that the foregoing general description and the following detailed description as well are exemplary and explanatory of the invention but are not restrictive thereof.

Referring now in detail to the accompanying drawings which show the present preferred embodiment of the invention there is illustrated a multi-unit winding machine having a plurality

of winding units 30 arranged in two parallel aligned series facing in opposite directions with the back sides of the winding units of one series adjacent to the back sides of the winding units of the other series.

These winding units are of substantially conventional construction and each comprises a driving roll 32 carried and driven by shaft 33 which is rotatably journaled in bearings 34, all of the rolls 32 for a given series being mounted on a single shaft 33, suitably driven. Bearings 34 are mounted on a unit frame 39, and these unit frames are securely fastened to the main frame 40 of the machine.

For rotatably supporting the core 44 on which the package 45 is to be wound, there is provided a wooden core 42 (or an iron cone shell not shown) which is freely rotatable on a spindle 43 pivotally supported in the end of an arm 46 which is rotatably mounted by means of collar 47 on a shaft 48, extending from one end of the machine to the other, the arms 46 being held against easy movement by a heavy spring 49 fast to the collar 47 and having a rolled end 50 which rides in the groove 51 of collar 52 fast to the shaft 48. The arms 46 for each series of winding units are mounted on the common shaft 48, but extend therefrom in opposite directions, and hold the cone spindles 43 at such an angle that substantially full contact may be established between the package core 44 and the driving roll 32, thereby rotating the package core by frictional contact with its surface to wind yarn on the package.

Means are provided for traversing the yarn throughout the desired distance on the package core and for this purpose a cylindrical traverse cam is mounted adjacent to the driving roll 32 and in parallelism therewith, the traverse cams for all of the winding units of each series being mounted on and driven by a common shaft 55 which is suitably driven from a motor (not shown) provided with means to automatically recurrently vary the speed of cam shaft 55. The traverse cam and thread guide may be of conventional construction but in the illustrative embodiment comprise a thread guide 60 supported at the end of a finger 54 which is reciprocated in a controlled varied timed relation to the rotation of shaft 33 by means of the usual cam groove in the cylindrical cam 56 on shaft 55. Thus as the package is rotated by the driving roll 32, yarn Y is traversed back and forth along the length of the package core by the thread guide 60 to lay it on the package in uniform layers.

The yarn supplied for winding is carried on bobbins 70 which are tubular and have a mass of yarn 71 thereon, being shown as the type of bobbin which would be produced by conventional spinning machines. These bobbins are supported on movable bobbin supports 71. A tender 160 is adapted to move around the machine and successively into operative contact with units 30, the tender being mounted to move on a straight trackway 155 having curved end portions 156 (Figure 1).

Suitable driving means are provided for moving the tender past each unit, such means comprising, if desired, an electric traction motor operating through gears or by belts to cause the tender to move around the machine.

As the yarn is drawn from the active bobbin it passes upwardly, over a guide bar 342, between the tension washer 351 and the bottom washer 349, over the thread bar 103 and is guided onto the package by the traversing guide 60.

The traverse mechanism is shown more in detail in the prior patent to McKean, 1,992,757, the structure of which is substantially duplicated here. The prior patent to McKean shows a typical form of drive for the driving roll 32 and the cylindrical cam 56, and are so shown. Thus each of the winding units has friction means for driving the package by its surface, and for winding on the package a yarn which is traversed by a reciprocating thread guide, while the yarn is drawn through the tensioning mechanism from the yarn supply mass or bobbin.

Each unit is also provided with suitable means for automatically raising the package out of contact with its driving roll to stop its winding when the yarn breaks or is exhausted from the supply bobbin.

Figure 2 shows the position of the parts after the starting handle 110 has been released, and 20 while the machine is in operation. As will be noted the thread bar 103 has been lowered so that the thread now runs in the guide 60, and also shows the parts in running position, with the dropwire 112 held in lowered position by the tension of the thread.

Raising of the dropwire 112 to position 112A causes roller 121 to engage the cam 120 thereby releasing latch 124 and allowing the handle 110 to be raised to a stop position carrying with it arm 30 108 which moves the ratchet finger 106 forward about its pivot while it is in engagement with the teeth of rack 104, thereby swinging the package upwardly regardless of its diameter.

The winding mechanism may be restarted as 35 soon as a new yarn has been joined to the end of the yarn on the package.

As a new bobbin 70 is dropped onto a pin 78 of support 77 to replenish the bobbin supply, the operative keeps hold of the free end of the 40 yarn and clips the yarn end in the slot 334 in a hook 335 which is also supported on the upper end of a shaft 74, extending from support 77, thereby holding the free end of the yarn ready for the assembling and knotting operations which 45 are later to be performed.

In accordance with the present invention, pneumatic means are provided for loosening the free end of the yarn from the package 45 being wound and for drawing from the package a pre-determined length of this yarn. For this purpose there is provided a centrifugal blower 240 which is mounted on and carried by the tender 160 and is driven at high speed from a suitable motor or other prime mover, 244, the speed of 50 the blower being sufficient to develop a rather high velocity of air. Supported on and above the tender is a sheet metal air conductor 250 which extends upwardly and toward the package 45 being wound, and this conductor comprises a pressure duct 251 and a suction duct 252, the pressure duct partially surrounding the suction duct throughout most of its length. The suction duct at its lower end 253 is connected to the intake of the centrifugal blower 240, while at its other end, 55 the suction duct terminates in a relatively thin suction slot 254 which extends lengthwise of the package 45, and is preferably of a length substantially equal to or slightly longer than the package being wound. At its lower end, the air conductor 250 forms a chamber which includes the fan 240.

The suction duct 252 is composed of a sheet metal member rectangular in cross section which terminates in a circular portion 255, connected to 70 a flexible hose 256 of relatively large diameter

which forms the suction connection to the intake of the fan. Thus the fan 240 being driven continuously as the tender moves, a relatively strong blast of air issues from the forward end 258 of the air conductor which is directed against the surface of the package 45 and tends to loosen and dislodge the end of yarn sufficiently to free it almost immediately from the layers of yarn on the wound package, thereby allowing the loosened end to be picked up more readily and drawn into the suction duct 254 by the air being sucked therethrough.

Means are provided for periodically projecting the suction duct 252 toward the package being wound, 45, as the tender moves past the winding unit so as to enhance and render effective the suction operating through the slot or duct 254. As particularly shown in Figures 3 and 4, the suction duct 252 is mounted on the tender by means of links 261, one link being pivoted on a pivot pin 262 carried on either side of the tender frame, the links having their upper ends pivotally mounted on a rod 263 supported by strap 264 attached to either side of the suction duct 252.

The forward end of the suction duct 252 is provided with a strap 266 extending upwardly therefrom and having a roller 267 freely rotatable at its upper end and adapted to ride on the upper surface of a cam plate 269 projecting upwardly from the air conductor 250, strap 266 extending through a suitable slot in the upper wall of the conductor 250. The shape of cam 269, and the action of the link 261 are such that the suction duct 254 moves toward the package in a generally forward and slightly downward direction.

Also connected to the shaft 263 is a link 270 having its forward end connected to the upper end of bell crank 271 which is mounted for rocking movement about a shaft 272 carried by the tender frame, and extending in a direction parallel to the direction of travel of the tender. Bell crank 271 is provided with a forwardly extending arm 273 to the forward end of which is attached the cam member 275. Cam member 275 engages with hub 296 at the adjacent end of starting lever 110 so as to depress arm 273 and the cam member 275 as the tender moves past starting lever in knockoff position, thereby rocking the bell crank 271 to project the suction duct 252 until its slot 254 is closely adjacent the package 45.

The finding of the free end of the yarn on package 45 is facilitated and expedited by the blast of air issuing through the pressure nozzle 258 which prevents the adherence of the free end to the package as might otherwise occur.

Preferably, and by any suitable means, as by an idler roller 280 mounted to move with duct 254 by a bracket 281 and insertable between driving roller 32 and the package 45 as shown dotted in Fig. 3, the package 45 is reversely rotated at this stage, and yarn is paid off from it and sucked into the suction duct 252, and the free end is carried into the flexible hose 256. Cam 275 is released from hub 296, in proper timed relation by movement of the tender, to insure that the free end of the yarn has been drawn into the flexible hose 256 but not into the fan 240, and as the suction continues the yarn is laid along the bottom wall of the suction duct 252 and across slots 290 and 291 shown particularly in Figure 5, for the purpose hereinafter described.

Suction duct 252 is fully restored to its original position as shown in Figure 3 by the positive action of a cam 295 carried by lever 273, operating on the hub 296 projecting from the end of start-

ing lever 110, and the suction duct 252 remains in this position until it approaches the next winding unit for the corresponding reversing and end finding operations.

As particularly embodied, the invention includes means to permit removal of the free length of yarn in the duct 252 from the duct. To this end the lower trailing edge of duct 252 is preferably formed with a narrow slot 293 (Figure 5) extending from the suction slot 254 past slots 290 and 291 in duct 252, so that a hook passing straight through either of the slots 290 or 291 may remove the yarn sideways through the duct.

Means are provided for engaging the yarn in the duct 252 and for removing it through the side slot 293. For this purpose each winding unit is provided with a hook 335 mounted on U-shaped arms 395 which in turn are supported on the upper end of the shaft 74. Hook 335 is formed as an angled plate extending parallel to the direction of travel of the tender and having a lower slot 334 and an upper slot 399, these slots both being of considerable length, parallel to the direction of travel of the tender and opening rearwardly with respect to the direction of travel of the tender, being held, however, rigidly with respect to the winding unit so that the tender moves past them. The arms 395 hold the hook 335 in a fixed position so that the upwardly extending portion of hook 335 may pass through slot 291 as the tender travels.

By this relative movement, the free end of the yarn overlying the slot 291 is threaded into the slot 399 and further movement of the tender causes the yarn to be pulled sideways, the free end of the yarn having been subjected to tension by the suction and velocity of the air in the hose 256. The free end of the yarn is thus moved from its position to a position close with respect to the leading end of the supply bobbin, the free end of which had been previously inserted in slot 334 as the operative dropped the bobbin onto the spindle 78. Further movement of the tender causes the free ends of the yarns to be located near each other on the side of hook 335 away from the package, and ready for the tying or knotting operation which may be performed manually, or with a manually actuated mechanical knotter, or may be carried out automatically.

As illustrated, a knotter 310 is carried by the tender by a bracket 248 and rod 311, and depends from its trailing side with its yarn receiving notches in a position to receive the yarn ends assembled on hook 335 on further movement of the tender, and other means such as dogs 312, 316 and 318, are provided for actuating the knotter to cause the completion of the knotting operation by further relative movement with respect to the winding unit.

As illustratively shown, the knotter is of the conventional type manufactured and sold by Mill Devices Company and is adapted to tie a weaver's knot, this conventional type of knotter having been modified by the addition of any suitable actuating members to permit it to be mechanically actuated if desired by the travel of the tender past the winding units.

As the tender in its regular travel around the winder passes a winding unit it advances the knotter 310 past each winding unit 30 and during the said advancement the knotter 310 performs its functions of uniting and trimming two strands of yarn.

Simultaneously with the extending of the suction duct 252 the knotter 310 is lowered and advances in its travel; also the nozzle end 254 of the

suction duct 252 has been brought into close proximity to the peripheral surface of the wound package 45 of yarn and means, previously described, have caused the package to start to unwind. With the end of the strand on the package having been loosened, found and sucked and drawn away to a length extending beyond the transverse slots 290 and 291 in the suction duct, the hook 335 draws the extended strand out of the suction duct 252 through the long narrow slot 293 and the suction duct 252 is then retracted up and back to its normal idle position.

Immediately following the knotting operation, the knotted 310 will have advanced in its regular longitudinal travel with the tender being swung up and back to its normal idle position.

The complete knot tying operation is repeated at each winding unit where the suction duct is caused to function when a winding package has been stopped due to an end of a strand of yarn having passed off the drop wire detector and allowed said detector to move out of its yarn winding position.

After the trailing end of the yarn on the package 45 has been joined to the leading end of the yarn of the new supply, the winding of package 45 may be restarted, and in its further movement the tender preferably causes starting the arm 110 to be moved to restarting position and returned to running position.

It is generally desirable that the yarn be wound under tension, and usual means 351 may be provided for tensioning the yarn as it is wound.

Specifically referring to Figures 6 to 9, which show certain of the cam actuating devices as cam 275 is moved across hub 296, with hub 296 already in its extreme upper knocked-off position with the package also in knocked-off position, cam 275 is pushed downwardly projecting the suction nozzle toward the package.

Curved surface 275' merges into the flat 275'' to hold the suction nozzle close to the package for a short period of time sufficient to cause the end of the yarn on the surface of the package to be freed, sucked into the nozzle 254, and a sufficient length of free yarn paid off by the reverse rotation of the package 45 so that the free end of the yarn is drawn into the suction nozzle some distance past slot 291.

As hub 296 rides off the end of flat 275'', the upper face of hub 296 is engaged by the under-face of the cam 295, also mounted on the arm 273 thereby positively rocking bell crank 271 in a counter-clockwise direction to retract suction duct 252 thereby interrupting the reverse rotation of the package 45 and restoring the duct to its normal position where it remains until it reaches the next winding unit.

The operation of the illustrated apparatus may be summarized as follows:

Assuming that the several winding units 30 are operating normally with the motors driving the shafts 33 and the cam shafts 55. The travelling tender 160 is moving around the group of winding units, and the fan 240 is at the same time driven continuously to create suction in the duct 252 and pressure in the duct 250.

Most of the winding units, except a few in front of the tender, are still winding in the normal manner but certain of the winding units have stopped winding due to exhaustion of the yarn supply mass or breakage of the yarn, in which case those particular units will be at rest with the package 45 out of contact with the still rotating driving roll 32.

In each active winding unit, the package 45 being wound is resting on its driving roll 32 and is being rotated, while supported on the arm 46, to draw yarn from the yarn supply bobbin 71 through the yarn guide which is traversed back and forth across the package by means of the cylindrical cam 56 driven by shaft 55. In each winding unit, yarn detector 112 is held down by the yarn under normal winding tension, but in case the yarn breaks or becomes exhausted, detector 112 is raised to cause the package 45 to be raised from its driving roll 32 and at the same time starting lever 110 is raised to its upper or knocked-off position thereby stopping the winding on that particular winding unit.

Specifically, in accordance with this invention, as soon as the tender 160 approaches a winding unit which has stopped for any reason, the relative movement of the tender and winding unit causes the actuation of the various parts through the coaction of the different cam mechanisms. The hub 296 at the end of the starting lever 110 engages with the inclined surface 275' of cam 275 thereby causing arm 273 to be depressed so as to project the suction nozzle 254 towards the stopped package.

The time of extension of the suction nozzle is such as to provide for drawing an approximately uniform length of yarn from the package into the suction duct.

During the period the suction nozzle is extended, air under pressure and at a considerable velocity is issuing from the forward end 258 of the air duct 250 and blows directly against the package thereby facilitating the freeing of the yarn end from the package so that the yarn end is almost immediately found by and sucked into the suction nozzle 254.

Prior to the retraction of the nozzle from the package, yarn engaging hook 335 passed through slot 291 to remove the yarn end, thereby assembling the end of the yarn extending from the package with the end of the yarn extending from the reserve bobbin, or other yarn supply, and which is held in the slot 334 of the same hook member.

The suction duct is then retracted and positively restored to its original position by engagement of the hub 296 with the under face of the inclined cam member 295, hub 296 being at that time supported by means of the roller 277 which rides across the upper face of the plate 297 carried by the tender.

After the yarn ends have been assembled and the suction duct 252 has been retracted, the ends of the two strands of yarn are tied together for example by the knotted 310 which has been swung down and is actuated to tie the knot, the knotted being moved by the tender while the rack is held stationary on the winding unit.

Thereafter, the tender continues movement to the next winding unit, and the operations previously described are repeated on that unit if the unit has been stopped by exhaustion or breakage of the yarn.

When the packages have been built to the proper size, the operative individually removes them as they become full, thereby preventing overwinding of the packages.

While the invention has been generally and specifically described with respect to apparatus having a plurality of units and one blowing and suction draw off device moving relative thereto, it is obvious that the invention broadly embraces apparatus where each unit has its separate suc-

tion air duct operating when needed for the purpose described, with its own hook for picking up the thread or yarn end sucked into its duct.

The invention in its broader aspects is not limited to the specific mechanisms shown and described but departures may be made therefrom within the scope of the accompanying claims without departing from the principles of the invention and without sacrificing its chief advantages.

What we claim is:

1. In a winding machine, the combination of a yarn package core, means to rotatably support said core to permit winding of yarn thereon, means to apply air under pressure to the yarn on said core to loosen an end thereon, means to apply suction to said end to withdraw a length thereof, and means to lay said length in a predetermined path, for the purpose of future assembly with another yarn end.

2. In a winding machine the combination of means for supporting and rotating a yarn package core for winding yarn thereon from a supply bobbin, means for applying suction over the length of said package core for exploring for a free end of yarn thereon, means for simultaneously blowing air against said package core for freeing said end, means for periodically moving said suction means and said package core relative to one another to facilitate said exploring, and means for withdrawing the length of yarn drawn by suction from said package core from its normal path to a predetermined location for tying with the end of yarn on a supply bobbin.

3. In a winding machine, the combination of a yarn package, means for supporting and rotating said yarn package, means to apply suction at a point proximate to the periphery of said yarn package, means to apply air pressure against the yarn package to free an end of yarn thereon, and means to suck off a predetermined length of the freed end of yarn from said package.

4. In a multi-unit winding machine the combination of a travelling tender moving past the units, an air suction duct moving therewith and adapted to be periodically projected toward a winding package, to free an end of yarn thereon and draw off a length thereof by suction, means to lay the drawn yarn in a predetermined position across two slots in said duct for subsequent assembly with another end of yarn, and means to pick up said drawn yarn and carry it from said slots to a position for tying with said other end of yarn.

5. In a multi-unit winding machine, the combination of means for supporting and rotating a package core on which yarn is to be wound, a divided air nozzle and means for blowing and sucking air through the different parts of the nozzle to free a yarn end from the package and suck the yarn end into the nozzle.

6. In a multi-unit winding machine, the combination of means for supporting and rotating a yarn package, a tender movable relatively past the package, a wide air nozzle carried by the tender and movable toward and from the package being wound to suck a yarn end from the package, said nozzle comprising two slots extending side by side through one of which air is blown while air is sucked through the other.

7. In a multi-unit winding machine, the combination of means for supporting and rotating a yarn package, a travelling tender having a suction duct adapted to periodically move close to the package, said suction duct having a narrow

slot extending substantially parallel to the movement of the tender and through which a yarn end extending from the package may be removed by suction, and means to control the time of application of the suction to control the length of yarn sucked through said slot, to provide a uniform length of draw at all times.

8. In a multi-unit winding machine, the combination of a travelling tender, a blower, and an air duct connected therewith, said blower and duct being carried by the tender and the air duct extending to be closely adjacent a winding package, said duct being divided to provide suction and pressure portions directed at the package and being provided to draw a predetermined length of yarn from said winding package.

9. In a multi-unit winding machine, the combination of a frame, means thereon for supporting and rotating a yarn package, a travelling tender having respectively suction and blowing ducts to move close to the package to suck and blow on the package, said suction duct having a narrow slot extending along an edge thereof, said duct having two intersecting slots parallel to the path of tender travel, stationary hooks fixed on the frame and means holding a reserve yarn end adjacent one of the hooks, said hooks being movable through the slots to remove a yarn from the duct through the first slot and to assemble said yarn with the reserve yarn held by said holding means.

10. In a multi-unit winding machine, the combination of a frame, means thereon for supporting and rotating a yarn package, a travelling tender having respectively suction and blowing ducts to move close to the package to suck and blow on the package, said suction duct having a narrow slot extending along an edge thereof, said duct having two intersecting slots parallel to the path of tender travel.

11. In a multi-unit winding machine, the combination of means for supporting and rotating a yarn package, a travelling tender having a suction duct to move close to the package, said suction duct having a narrow slot extending substantially normal to the movement of the tender from which a yarn end extending from the package may be removed, and stationary means adapted to engage the yarn and remove it laterally from said slot in the duct, as said travelling tender moves said duct past said stationary means.

12. In a multi-unit winding machine, the combination of means for supporting and rotating a yarn package, and a tender movable relatively to the package having a suction duct to move close to the package, said suction duct having a narrow slot extending along the trailing side of the duct, said duct having two slots parallel to the path of tender travel with the two slots intersecting said narrow slot at the trailing edge of the duct.

13. In a multi-unit winding machine, the combination of means for supporting and rotating a yarn package, a tender movable relatively to the package having a suction duct to move close to the package, said suction duct having a narrow slot extending along the trailing side of the duct, said duct having two slots parallel to the path of tender travel with the two slots intersecting the narrow slot at the trailing edge of the duct, and hooks movable relatively through the slots to remove a yarn from the duct through the first slot.

14. In a multi-unit winding machine, the combination of means for supporting and rotating a

yarn package, a travelling tender having a suction duct to move close to the package, said suction duct having a narrow slot extending substantially normal to the travel of the tender and in which a yarn end extending from the package is located and may be removed therefrom and means crossing said slot and thereby engaging the yarn for removing the yarn laterally from the duct.

15. In a multi-unit winding machine, the combination of means for supporting and rotating a yarn package, a travelling tender having an upwardly and inwardly directed suction duct movable toward and from the package, said suction duct having a narrow slot extending along the lower, trailing side of the duct the bottom of said duct having a second slot parallel to the path of tender travel with the slots intersecting at the trailing edge of the duct, and a stationary hook associated with means to hold yarn, said hook being movable relatively through the second slot to remove the yarn end laterally from the duct.

16. In a multi-unit winding machine, the combination of means for supporting and rotating a yarn package, a travelling tender having a suction duct to move close to the package, said suction duct having a narrow slot extending substantially normal to the movement of the tender and from which a yarn end extending from the package may be removed, a second slot intersecting the narrow slot and parallel to the path of movement of the tender, a hook mounted for relative movement to both of the slots and passing through the second slot to engage a yarn lying across the second slot and remove it through the narrow slot as the tender moves.

17. In a multi-unit winding machine, the combination of means for supporting and rotating a yarn package, a tender movable relative past the packages, a wide air nozzle carried by the tender and movable toward and from the package being wound to suck a yarn end from the package, means movable to reverse the rotation of the package, means for timing the reversal of the package to control the length of yarn drawn from the package, said nozzle comprising two slots extending side-by-side through one of which air is blown while air is sucked through the other.

18. In a multiple unit winding machine, the combination of means for supporting and winding a package of yarn, a support for a yarn supply mass from which a yarn is wound on the package, a tender movable relatively past the winding units, a blower mounted on the tender, a suction duct having a nozzle adjacent to the package, said duct having a long narrow slot, a plurality of hooks mounted on the winding unit, said hooks retaining a yarn end from a supply mass, a plurality of slots in the duct intersecting the narrow slot and through which the hooks may move relative to the slots, said duct being connected to the blower to suck a yarn end from the package into the duct to overlie the plurality of slots, and means carried by the tender for removing the yarn end from the duct, for assembling the yarn end with a reserve end.

19. In a multi-unit winding machine, the combination of means for supporting and rotating a package core on which yarn is to be wound, a divided air nozzle movable towards and from the package and means for blowing and sucking air through the different parts of the nozzle to free a yarn end from the package and suck the yarn end into the nozzle.

20. In a multi-unit winding machine, the combination of means for supporting and rotating a package core on which yarn is to be wound, and a thin wide air nozzle mounted for movement past the package surface substantially as wide as the length of the package and having a slot formed in a wall of said nozzle, and means for sucking air through the nozzle to draw an end of yarn into the nozzle and placing same in said slot for subsequent removal through said slot for knotting with a supply end.

21. In a multi-unit winding machine, the combination of means for supporting and rotating a package core on which yarn is to be wound, a thin wide air nozzle mounted for movement past the package surface substantially as wide as the length of the package and means for sucking air through the nozzle to draw a free end of the yarn of predetermined length into the nozzle and means for removing the yarn end from the nozzle to assemble it with a supply yarn end including stationary means for engaging the yarn end and laterally withdrawing same under movements of the nozzle past the package.

25. 22. In a multi-unit winding machine, the combination of means for supporting and rotating a yarn package, a travelling tender having a suction duct and a pressure duct both adapted to periodically move close to the package, said ducts having narrow nozzle mouths extending substantially parallel to the travel of the tender and through which a yarn end blown from the package by the air pressure may be removed by suction, and means to control the length of yarn sucked through said mouth, to provide a uniform length of draw at all times, said means to control the length including a reverse mechanism for said yarn package.

23. In a multi-unit winding machine, the combination of a travelling tender, a blower, and an air duct connected therewith, said blower and duct being carried by the tender and the air duct extending to be closely adjacent a winding package, said duct being divided to provide suction and pressure portions directed at the package and being provided to draw a predetermined length of yarn from said winding package, by reversing mechanism acting periodically on said winding package to unwind same.

24. In a winding machine the combination of means for supporting and rotating a yarn package core for winding yarn thereon, means to support an active supply bobbin, means for blowing air under pressure over said package core to free a yarn end thereon means for applying suction over the length of said package core for exploring for said free end of yarn, means for periodically moving said suction and blowing means toward said package core and into proximity with the yarn thereon to permit said free end of yarn to be withdrawn by suction, and means for withdrawing the length of yarn drawn by suction from said package core from its normal path to a predetermined location for tying with the end of yarn on a supply bobbin, said means being arranged so that said predetermined location is closely proximate to said active supply bobbin.
